UNITED STATES PATENT OFFICE.

JAMES CORBETT, OF TORONTO, ONTARIO, CANADA, ASSIGNOR OF ONE-HALF TO
BENJAMIN COHEN, OF TORONTO, CANADA.

ROTARY PUMP.

Application filed January 27, 1927, Serial No. 164,107, and in Canada January 28, 1926.

The invention relates to improvements in rotary pumps as described in the present specification and shown in the accompanying drawings which form part of the same.

5 The invention appertains in particular to the type of rotary pump in which an offset rotor revolves at a tangent to the casing and vanes or pistons sweep the crescent-shaped chamber formed by the eccentricity 10 of the rotor. The salient object of the present invention is to provide an improved mounting for vanes, one which reduces wear to a minimum and materially prolongs the life of the vane-carrying mechanism.

15 A general object of the invention is to produce an efficient and durable rotary pump which will withstand hard usage and give good service.

With these objects in view the invention 20 consists in the novel construction and arrangement of parts as described in the specification, shown in the accompanying drawings and claimed in the claims hereunto appended.

25 Referring to the drawings, Figure 1 is a vertical sectional elevation of a rotary pump embodying the present invention.

Figure 2 is a front elevation with the cover plate removed in order to depict the 30 mechanism therebehind.

Figures 3 and 3^A illustrate a slight modification of the invention, which consists of a renewable slide block mounting for the vanes.

35 In the drawings, the reference numeral 1 indicates generally the stationary casing, which is preferably a casting having one side closed and the other open, the open side being flanged to receive the usual cover plate 2. The casing has the ordinary inlet and outlet openings 18.

The rotor 3, of hollow cylindrical shape, is diametrically smaller than the casing bore and tangentially positioned therein as customary. It has a central boss 13, through 45 which the shaft 12 passes and is keyed to secure a driving connection. The shaft is journalled on one side of the rotor by a bearing integral with the casing, while on the other side it has a journal 14 supported in a bearing 11 integral with the removable plate 2. The shaft projects from the casing for the purpose of being connected to some form of motive power.

55 The bearing 11 includes a boss constructed

integrally with the inner side of the cover plate 2, which boss extends into the rotor and is machined eccentrically to the rotor axis but concentrically with respect to the casing bore, thus constituting an eccentric 60 7 for the purpose of controlling or guiding the vanes.

Slidably projecting through the periphery of the rotor is a pair of diametrically opposite vanes 4 and 5, which are retained by a 65 ring 6 fastened to the flange 15 of said rotor adjacent to and preferably bearing against the inner face of the recess 17 of the cover plate 2. These vanes are joined to each other by means of ribs 8, spaced apart as 70 shown in Figure 1. The inner ends of the vanes are provided with a pair of opposing sliding blocks 9, 9, which have flat faces slidably engaging non-opposed flat bearings of a rotary block 10 that is a running fit 75 on the eccentric 7. The slots in the rotor in which the vanes operate are flanged as at 15' in order to increase the bearing area.

With a view to increasing suction and discharge, the vanes 4 and 5 are equipped with 80 feather blades 29.

In the operation of this pump, it will readily be seen that upon motion being imparted to the rotor 3 it carries the vanes 4 and 5 around with it. Due to the fact that the 85 vanes are mounted as a unit upon the eccentric, whose true centre is offset with respect to the rotor axis, the vanes have a lateral sliding action on the centre block 10. This lateral movement is equal to the centre-to- 90 centre distance of the rotor and casing bore. The large bearing surface between the blocks 9 and the centre block 10 provides a very efficient mounting for the vanes, which resists wear and prolongs the life of this mechanism.

In the modified form of the invention shown in Figures 3 and 3^A the integral sliding blocks 9, 9 are replaced by removable sliding blocks 23 in order that when worn 100 same may easily be renewed. This renewable construction is accomplished by the provision of a pair of spaced bosses 20, integral with each vane and joined to ribs 19. A sliding block 23 is placed between 105 each pair of bosses and mounted on a pin 22 passing therethrough, so that its part 24 will slide upon the rotary block 10.

What I claim is:

1. In a rotary pump of the class described, 110

- a rotor, a stationary eccentric, a plurality of vanes for passing through the periphery of the rotor, a member rigidly carrying the vanes as a unit, said member being provided 5 with opposed flat bearing surfaces, and means revolvably engaging the eccentric to present non-opposed flat faces for sliding engagement with the bearing surfaces of the said vane carrying member.
- 10 2. In a rotary pump of the class described, a rotor, a stationary eccentric, a plurality of vanes for passing through the periphery of the rotor, means connecting the vanes as a rigid unit, sliding blocks carried by said 15 means and provided with opposed flat bearing surfaces, and means revolvably engaging the eccentric to present non-opposed flat faces for sliding engagement with the bearing surfaces of the sliding blocks.
- 15 3. In a rotary pump of the class described, a rotor, a stationary eccentric, a plurality of vanes for passing through the periphery of the rotor, a member rigidly carrying the vanes as a unit, said member being provided 20 with opposed flat bearing surfaces, and a rotary block revolvably engaging the eccentric and presenting non-opposed flat faces for sliding engagement with the bearing surfaces of said vane carrying member.
- 25 4. In a rotary pump of the class described, a rotor, a stationary eccentric, a plurality of vanes for passing through the periphery of the rotor, means connecting the vanes as a 30 rigid unit, renewable sliding blocks carried by said means and provided with opposed flat bearing surfaces, and means revolvably engaging the eccentric to present non-opposed flat faces for sliding engagement with the bearing surfaces of the sliding blocks.
- 35 5. In a rotary pump of the class described, a rotor, a stationary eccentric, a plurality of vanes for passing through the periphery of the rotor, means connecting the vanes as a rigid unit, sliding blocks, means removably attaching said sliding blocks to the vane carrying means, and means revolvably engaging the eccentric to 40 present flat faces for sliding engagement with the sliding blocks.
- 45 6. In a rotary pump of the class described, a motor, a stationary eccentric, a plurality of vanes for passing through the periphery of the rotor, ribs connecting said vanes one to the other as a unit, a pair of spaced bosses disposed on each side of the eccentric and carried by the said vane unit, a sliding block placed between each pair of bosses, a pin passing through each sliding block and the corresponding bosses, and a rotary block revolvably engaging the eccentric and 50 presenting flat faces for sliding engagement with the sliding blocks.

Signed at the city of Toronto in the county of York, and Province of Ontario, this 1st day of September, 1926.

JAMES CORBETT.
